WILLEM PIETER CORNELIS VAN DER HORST, OF THE HAGUE, NETHERLANDS

METHOD FOR TRANSMITTING A PLURALITY OF COMMUNICATIONS

Application filed December 4, 1930, Serial No 500,149, and in the Netherlands December 4, 1929.

The present invention relates to the simultaneous transmission or broadcasting of a plurality of communications, each of which is separately recorded either mechanically, for example on a wax cylinder; magnetically, for example on a magnetized wire or band; or in any other well-known manner, e. g. optically.

According to this invention use is made of 10 the pauses occurring in a communication, these pauses being filled by one or more other communications, so that the transmitting even with one transmitter on one wave-length can be effected in a shorter time than if the 15 communications were transmitted consecutively.

It is known that during a speech, the pauses occurring between the various words and often even between the syllables of the words, 20 may constitute a total of 75% or 80% of the duration of the speech.

According to the invention in the transmission of previously recorded messages or communications, the gaps in one message are 25 filled up with parts of other messages without the necessity of widening. A certain secrecy as well as a saving in time is thus obtained.

During the transmission of a communication recorded for example on a band, a second band is put into operation as soon as the 30 oscillations or oscillatory currents due to the first band cease. The second band in turn transfers its communication to the transmitter until such time as the first band, which 35 continues in operation, again causes the production of oscillatory currents, at which time the second band is stopped automatically.

In carrying out the invention a branch circuit is arranged in the transmitted circuit, which branch circuit influences a contact in 40 such manner that it remains open as long as the oscillations are maintained. When these cease, this contact closes a circuit which causes a second band to start. When the oscillations due to said second band are no longer produced, a third band is set into motion unless 45 in the meantime the first band has again begun to transmit oscillations, in which case the first band alone is operative. Each time a

new circuit is made, a signal or impulse is transmitted which influences contacts on the receiver.

The transmitter and receiver may be so constructed that in case oscillations are not 55 transmitted from any of the three bands, a fourth band is put into operation, etc.

According to a modification of the system comprising the invention, each band in turn is arranged to become the continuously moving band, so that the several communications are more equally transmitted. The contacts are arranged in such manner that band II becomes band I, band III becomes band II, and band IV becomes band III after a certain 60 number of pauses in the oscillations received from the continuously moving band. It will be understood that when this modification is not made, a subsequent band, for example the fourth, usually remains idle for too long 65 periods as the earlier bands transmit practically continuous oscillations.

The device may be adjusted in such manner that the switch-over is effected only by 70 pauses of a duration longer than a predetermined time, shorter pauses being ineffective.

By way of illustration certain details of a possible arrangement, will be discussed, solely for explanatory purposes, in connection 75 with the accompanying drawings.

Fig. 1 is a schematic view, showing a number of bands,

Fig. 2 is a fragmentary schematic view illustrating how the bands are brought into action,

Fig. 3 is a general schematic view, illustrating the details for the application of the principle demonstrated by Fig. 2,

Fig. 4, a further schematic view, shows 80 how the bands are put into operation and how they are stopped. (This mechanical device is disclosed merely to facilitate explanations; the use of a thermionic device, having practically no moments of inertia is possible and therefore recommended.)

Fig. 5 shows an extended application of a detail in Fig. 3. Fig. 1 shows a number of 85 circuits, each comprising a microphone 1, of such construction (not shown), that oscillations caused by breathing or such like are 100

- not recorded, so that the pauses become greatly accentuated from the very start. A source of current 2 and an electromagnet 3 record magnetically the oscillatory currents from 5 the microphone on a steel band 4. The first of these bands passes along a reproducing magnet 5 which reproduces the oscillatory current in the output line. The movement of the band is controlled by the device 7.
- 10 As long as the first band oscillates, the device 7, which will be further described hereinafter, prevents the further bands from moving. As soon as no further oscillatory current is received from the first band the device 15 7 effects a connection by which the following band is put into operation, and so on.
- Fig. 2 shows how in the magnet 5 an oscillatory current is induced which is sent to the transmitter through the line 8. A branch 20 current at 7 controls the movement mechanism 9 of the next band.
- Fig. 3 shows a more sensitive device where- 25 in the oscillatory current induced in the device 5 influences at 7 the system of a sensitive alternating current mirror-galvanometer. The light of a lamp 10 falls upon a photo- 30 electric cell 11, by which a current circuit of the mechanism of movement over combination 12 is closed. The band 4a starts and 35 the galvanometer 7a deflects, as a result of which light falls upon the cell 13a. If in the meantime a pause occurs in the band 4a, and assuming that in band 4 the pause still continues, the mirror of 7a returns into its position 40 of rest, throws light upon cell 11a and starts a third band. In the meantime the pause in band 4 has ended, the mirror 7 is brought out of its position of rest and the circuit 12 is interrupted. In order to prevent 45 the mirrors of the following galvanometers 7a, etc. from returning into their position of rest due to the above mentioned ending of the pause and thus starting up the bands 4a, etc., the cells 13, 13a, etc. have been provided. Their 50 circuits influence corresponding extra windings which prevent the non-moving bands from switching on the cells 11a, etc.
- Summarizing the following takes places:
- The band 4 transmits oscillations; the ray 55 of light is directed towards 13, 13a, etc., the circuits 11-12, 11a-12a, etc. are currentless. The band 4 now reaches a pause. The ray 60 of light is directed towards 11, while circuit 13 is currentless. Circuit 11-12 is live and 65 consequently band 4a moves. If then band 4a emits, the ray of light remains directed towards 13a. Consequently the third galvanometer is kept alive and 11a-12a, etc. remain currentless.
- Finally there are meters 6 in the main current circuits, which may be so adjusted, that if desired, the preceding band unit may put 75 out of action after any desired number of pauses.
- If in practice, pauses of a certain minimum

duration should give rise to an unsatisfactory operation of the set, the cells 11 should be adjusted in such manner that only after a certain lapse of time will they permit current to pass, or else cells possessing these properties should be used for such purpose.

Fig. 4 shows the device for stopping and putting in motion the band 4. The latter is moved by a disc 14 having soft iron discs attached on both sides. On the one side a magnetic system 15 rotates at the rate corresponding to the speed of the bands. On the other side there is a stationary magnetic system 16. A local current can now be so connected that if cell 11 permits current to pass due to the deflection of the galvanometer 7 (Fig. 3) it either influences the rotating magnetic system or the stationary magnetic system.

To stop the band the circuit of the rotating magnetic system 15 is broken and the 85 circuit of the stationary system 16 is closed. Consequently the disc is immediately caught and stopped.

To counteract the effect of the inertia of the disc, when the band starts or stops, the pick-up is caused to move in a direction opposite to the direction of the applied forces at a speed varying directly in accordance with the speed of acceleration or retardation of the band.

Fig. 5 shows an improvement by which another band is switched on only when a pause in the previous band is of sufficient duration.

Should pauses of a very short duration cause unsatisfactory working of the entire set 100 because of the inertia of the working parts, suitable adjustable cells or relays can be applied.

Fig. 5 shows at 7a retarding device to replace the adjustable cells or relays 11.

To demonstrate the principle, a second pick-up is used as a recording element. If we assume that pauses of a shorter duration than e. g. 1 second are not to be used, the pick-up 5 is placed before the pick-up 5b at a distance 110 corresponding to the displacement of the band in a one-second interval.

An extra current is applied to cell 7 (which to facilitate explanation has been shown as a mirror galvanometer), said circuit being controlled by the pick-up 5 connected to a light relay 17, which should likewise be adjusted to give a retardation of one second.

So long as the band emits oscillations, the two circuits support each other. If the pick-up 5 encounters a pause-gap, it records no more oscillations and the relay 17 breaks this circuit, but in this instance only after one second has elapsed. In this interval the pause-gap has covered the distance between pick-up 5 and pick-up 5b. The circuit of the pick-up 5b now also transmits no oscillations, so that the cell 11 is switched on. This occurs when the pause-gap is greater than one second.

If thereafter an oscillatory section of the band arrives at the pick-up 5, the circuit 18 is again switched on, but the current in this circuit alone is not able to deflect the galvanometer (inertia of cell 17) so that the deflection finally only occurs when the oscillatory section has arrived at pick-up 5b.

If a pause-gap shorter than one second passes the pick-up 5, there will be no time left for the light relay 17 to interrupt the current in circuit 18 and therefore the galvanometer-mirror remains in its position because an oscillatory current is impressed at 5 within the time of one second.

Thus it will be understood that when a shorter pause-gap than one second passes under pick-up 5b, the circuit of the latter only is made currentless, but since circuit 18 does not support the current flow, 11 cannot be switched on, so that this shorter pause is not used.

Finally the following may be observed with regard to the manner in which the mixture of speeches is divided into its component parts at the receiving side. For the receiving side the operation of the transmitter may be reversed. Then it is only the question how the received signs should be distributed upon the bands in question.

Besides the possibility of having transmitted the impulses of the mechanism of movement by modulators of different frequency and separating them in the receiver by means of filters, the following may be applied in the project as drawn. It will be noted that cells 11 etc. are arranged in the circuit to the transmitter. If the ray of light falls upon 11 etc. a current impulse will be produced in the transmitter, the strength of this impulse being proportioned to that of the source of light. By varying the strengths of the different sources of light (on the other hand the cells 11 themselves may be arranged for this purpose), the impulses in the receiving apparatus will also be of different strength.

In case the cells in question in the receiving apparatus have been turned to those various impulses of light and connected with the current circuit of the mechanism of movement of the corresponding band, it will be clear that the light impulse from e. g. cell 11, which puts into operation band 4a in the transmitter, also starts band 4a in the receiving apparatus. If—for example—for this purpose Kerr-cells are used in the receiving apparatus, said cells may be adjusted or constructed in such manner that only at a predetermined voltage is the polarization plane altered and the cell lets light pass, which is thrown upon the corresponding light relay, which then closes the circuit of the corresponding band.

It is essential of course that with the receiving apparatus similar precautions should

be taken as with the transmitter (cells 13, 13a, etc.) in order that a current impulse does not simultaneously influence another band indirectly.

Numerous modifications of my invention will readily occur to those skilled in the art. Accordingly, it is intended that the application be limited only by the scope of the appended claims.

I claim:

1. A method of transmitting in succession a plurality of communications, comprising recording said communications on records, transmitting the communications on one record, employing the gaps in the sets of oscillations transmitted from the first record for transmitting sets of oscillations from a second record, and stopping the transmission of oscillations from the second record when the pause between oscillations in the first record has terminated and continuing the transmission of oscillations from the first record.

2. A method of transmitting in succession a plurality of communications, comprising recording said communications on a plurality of bands, transmitting the oscillations from the first band, utilizing the pauses in the oscillations of the first band for transmitting the oscillations of a second band, utilizing the concurrent pauses in the oscillations of the first and second bands for transmitting the oscillations of the third band, terminating the transmission over the succeeding bands when the pauses in the preceding bands have terminated, and again transmitting the oscillations from the said preceding bands.

3. A method for transmitting a plurality of communications in succession, comprising recording said communications on a plurality of bands, utilizing the pauses in the oscillations of the first band to transmit oscillations from a second band, utilizing those pauses in the oscillations of the second band which are concurrent with the pauses in the first band to transmit oscillations from a third band, terminating the transmission of oscillations from the succeeding bands when the pauses in the preceding bands are bridged, continuing the transmission from the said preceding bands, and intermittently changing the sequential relation of the bands to each other whereby the transmission time is divided as equally as possible over the various bands.

In testimony whereof I affix my signature.

WILLEM PIETER CORNELIS van der HORST.
